UNITED STATES PATENT OFFICE.

C. ROY GLEASON, OF CHICAGO, ILLINOIS.

DESIGN FOR A CARAFE.

Application filed March 10, 1924. Serial No. 8,886. Term of patent 7 years.

To all whom it may concern:

Be it known that I, C. ROY GLEASON, a citizen of the United States, residing at Chicago, in the county of Cook and State of Illinois, have invented a new, original, and ornamental Design for Carafe, of which the following is a specification, reference being had to the accompanying drawing, forming a part thereof, in which the figure is a perspective view of a carafe, showing my new design.

I claim:

The ornamental design for carafe, as shown.

C. ROY GLEASON.
